(57) **CLAIM**

The ornamental design for a lighting fixture accessory, as shown and described.

DESCRIPTION

FIG. 1 is a front, right-side, and top perspective view of a lighting fixture accessory showing our new design;

FIG. 2 is a front, right-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cutaway view thereof taken in the front, right-side, and bottom direction with parts thereof cut off at line 9-9 of FIG. 7.

The design is shown with a symbolic break in its length. The appearance of any portion between the break lines forms no part of the claimed design.

The evenly dashed broken lines depict portions of the lighting fixture accessory in which the design is embodied that form no part of the claimed design.

The dot-dot-dash broken lines represent unclaimed boundaries of the design.
